UNITED STATES PATENT OFFICE

148,103

DESIGN FOR A COLOR HARMONY PALETTE

Edith F. Crane, Poughkeepsie, N. Y.

Application December 16, 1946, Serial No. 135,558

Term of patent 14 years

(Cl. D74—1)

To all whom it may concern:

Be it known that I, Edith F. Crane, a citizen of the United States, residing in the city of Poughkeepsie, county of Dutchess, and State of New York, have invented a new, original, and ornamental Design for a Color Harmony Palette, of which the following is a specification, reference being had to the accompanying drawing, forming a part thereof.

In the drawing:

Figure 1 is a top plan view of a color harmony palette showing my new design.

Figure 2 is a section on the line 2—2, Fig. 1.

Fig. 3 is a side view of the palette.

I claim:

The ornamental design for a color harmony palette, substantially as shown.

EDITH F. CRANE.
